(57) CLAIM

The ornamental design for a shoe, as shown and described.

DESCRIPTION

FIG. 1 is a front perspective view of a shoe showing my new design;

FIG. 2 is a side view thereof; and,

FIG. 3 is a rear perspective view thereof.

The broken line immediately adjacent to the rear of the shaded area defines the bounds of the claimed design and forms no part thereof. The broken line showing the generally triangular-shaped region within the shaded area forms no part of the claimed design. The broken lines depicting the remainder of the shoe form no part of the claimed design.
